INVENTOR:

Alfred Berney

UNITED STATES PATENT OFFICE.

ALFRED BERNEY, OF BOSTON, MASSACHUSETTS, ASSIGNOR TO NATHIEL A. DUTTON, OF SAME PLACE.

SPARK-ARRESTER.

SPECIFICATION forming part of Letters Patent No. 239,598, dated April 5, 1881.

Application filed September 21, 1880. (No model.)

To all whom it may concern:

Be it known that I, ALFRED BERNEY, a citizen of the United States, residing at Boston, in the county of Suffolk and State of Massachusetts, have invented certain new and useful Improvements in Spark-Arresters; and I do hereby declare the following to be a full, clear, and exact description of the invention, such as will enable others skilled in the art to 5 to which it appertains to make and use the same, reference being had to the accompanying drawings, and to letters or figures of reference marked thereon, which form a part of this specification.

15 My invention relates to spark-arresters, and is designed to arrest and convey sparks back to the fire-box from a spark-receiver by means of a jet of air or live or exhaust steam.

Nearly all locomotives are now fitted up with 20 an air-pump and a reservoir, and these can be used to force back the sparks to the fire-box, in connection with a steam-jet or not, or each can be used separately.

On many locomotives there is now used what 25 is called an "extended smoke-box" or arch to arrest sparks. This invention is designed to convey the sparks so collected back to the fire, to be consumed there. I attain these objects by the mechanism illustrated in the accompanying drawings, in which—

Figure I is a vertical section of a locomotive-boiler with my invention attached. Fig. II is a front elevation of the same.

The fire-box A is connected with flues B, 35 opening into the smoke-arch T, in which there is located a wire mesh or screen, C, and an exhaust-pipe, S.

In the extended smoke-arch E there is a hopper, D, so constructed that all the sparks drop 40 from screen C into it, down into chamber I.

The pipe K is attached to the chamber, and passes thence through a thimble, W, into the fire-box, over which is placed a small cast-iron shield, O.

45 Under the boiler is placed an air-reservoir, N, to which is affixed a pipe, M, provided with a suitable stop-cock, I. Said pipe extends forward and enters into the return-pipe K or chamber I, forming a jet of compressed air.

50 One or two steam-pipes, H, provided with

valves v, are connected to the steam-dome, and, curving downward, also enter the chamber I and assist in returning the sparks and air back into the furnace, and in burning them therein.

The smoke-stack F is of ordinary construction, as also the grate-bars Z.

The hopper D can be left out of the extension-front, if desired, as the shape of the arch will do almost as well; but I prefer to use the 60 funnel-shaped hopper D, as it prevents any clogging of the sparks by any jar of the engine.

The operation is as follows: When a fire is burning on the grate and the locomotive in motion, the exhaust-blast from the pipe S 65 causes a partial vacuum in the smoke-arch, and that draws air up through the grate-bars, and with the air a portion of the coal. These go through tubes B into smoke-arch T against wire screen C, the gases and steam passing 70 through said screen, but the sparks falling down into the hopper D, thence into chamber I through the pipe K, down shield O into the fire, to increase the speedy return of the sparks through pipe K. A jet of steam or air through 75 pipes M and H, which can be regulated by stop-cocks L and V, (one or both can be used, and the effect will be beneficial,) forces the sparks, &c., back into the furnace. The sizes of the pipes are regulated according to the sizes of 80 the locomotives—viz., the spark-pipes may be three inches in diameter and the steam and air pipes half an inch, while chamber I is about six inches in diameter and ten inches long.

I do not confine myself to one spark-pipe, as 85 two may be used, one on each side of the boiler, or the pipes may be inserted through the inside of the boiler.

If desired, the exhaust-pipe S can be tapped at the base and exhaust-steam be used instead 90 of live steam.

What I do claim as my invention, and desire to secure by Letters Patent, is—

1. The combination of an air-reservoir, N, air-pipe M, provided with stop-cock L, with 95 spark-chamber I and return spark-pipe K, with or without air-opening X, for returning sparks to the fire, substantially as specified.

2. The combination of an air-reservoir and one or more returning pipes or tubes with a fire- 100
